ATTORNEY

UNITED STATES PATENT OFFICE.

AUGUST TUTAY, OF SYRACUSE, NEW YORK.

CLOTHES-DRIER.

1,184,278.

Specification of Letters Patent. Patented May 23, 1916.

Application filed February 4, 1916. Serial No. 76,165.

To all whom it may concern:

Be it known that I, AUGUST TUTAY, a citizen of the United States, and resident of Syracuse, in the county of Onondaga, in 5 the State of New York, have invented new and useful Improvements in Clothes-Driers, of which the following, taken in connection with the accompanying drawings, is a full, clear, and exact description.

10 This invention relates to certain improvements in clothes driers, of the class embodying a series of radially extending rope carrying arms adapted to be spread when in use and collapse or fold against a central post 15 or standard when not in use.

An object of the invention is to produce a relatively strong, rigid, efficient drier of comparatively inexpensive construction that may be easily and readily moved from 20 lapsed to open position of the arms.

A further object resides in the formation and arrangement of the parts in such manner as to allow easy access to the raising and lowering means and to the clothes ropes 25 without interfering with any articles that may be hanging upon the drier.

A further object resides in increased efficiency by reason of the exposure of all of the clothes upon the drier to currents of air 30 by allowing free passage of the air radially and across the drier irrespective of the quantity of clothes thereon.

Other objects and advantages will appear from the following description, taken 35 in connection with the accompanying drawings, in which—

Figure 1 is a top plan view of the drier with a portion of some of the arms broken away. Fig. 2 is a side elevation, partly in 40 section. Fig. 3 is a horizontal section of a portion of one of the collars, showing the manner of attachment of the radially extending arms thereto. Fig. 4 is a view of one of the end castings for the radial arms. 45 Fig. 5 is a sectional view of the brace rope hook, showing its formation and means of attachment to the rope.

The invention, as shown, comprises a pair 50 of similar collar-like castings —1— and —2— respectively, each provided with a series of pairs of outwardly extending substantially parallel flanges —3— and —4—, respectively, each pair upon the casting —1— spaced to receive between them a radially extending arm —5— pivotally carried relatively to the collar —1— by a

threaded bolt —6— passed through the parallel flanges —3— and —4—, and having a threaded relation with one of them, as with the flange —4—.

In like manner, the pairs of flanges —3— and —4— upon the casting —2— receive between them the end of a brace bar —7— pivoted relatively to the collar —2— by means of pins —8— extending through the 65 parallel flanges and having a threaded relation with one of the same in like manner as the pin —6—. The opposite end of each brace bar —7— is pivotally connected to a respective one of the radial arms —5— by 70 a bolt —9— extending through the bar and the arm.

Each of the collars —1— and —2— are slidably mounted upon a central post or standard —10—, the collar —1— being preferably held from downward movement along the standard by a sleeve —11— adapted to be secured to the post at any desired elevation by a set screw —12—. The collar —2— is adapted for movement toward and from 80 the collar —1— for raising and lowering the radially extending arms —5—, and to accomplish this in an easy manner, each of the castings —1— and —2— is provided with a pair of diametrically disposed flanges 85 —13— preferably formed between an arm —4— and an arm —3— of different respective pairs of arms, the flanges —13— preferably projecting downwardly from the casting —1— and projecting upwardly from the 90 casting —2—, and this may be accomplished by merely inverting one of the castings.

A suitable rope —14— has its opposite ends passed through pulleys carried by the flanges —13— upon the collar or casting 95 —1— and secured in any suitable manner to the flanges —13— upon the collar or casting —2—. By pulling upon the intermediate portion of the rope, the drier is readily moved from collapsed to open position, and the standard —10— may be provided with a series of transverse openings —15— for the 100 reception of suitable means, as a pin —16—, upon which the collar —2— may rest when it has been moved to properly position the 105 arms —5—.

The end of each of the arms —5— is inserted between and secured to flanges —17— and —18— formed upon a rope carrying casting —19—, shown in Fig. 4. This casting 110 normally extends transversely of the arms —5— and is provided with a series

of rope receiving openings —20— and —21—, and each of the pins —6— is preferably provided with a substantially flat head having an opening or a series of openings —22— and the clothes carrying rope —23—, which may preferably be a single piece of rope, is passed alternately through an opening —22— in a pin —6— and a pair of openings —21— in the casting —19— and 10 then back and through an opening —22— in the next successive pin —6—. By stringing the rope in this manner, it extends substantially radially of the drier and is spaced from arms —5— a sufficient distance to allow the passage of air between clothes hung upon opposite sides of each arm —5— and to allow the radial passage of currents of air to all of the clothes hung upon the rope. 15 The drier is preferably provided with a series of brace ropes —24— having their intermediate portions engaged with a pair of openings —20— in the casting —19— and their opposite free ends provided with hooks —25— which, in collapsed condition of the 20 drier, may be carried by screw-eyes —26— and in open condition of the drier are adapted for engagement with openings —21— in the casting —19— upon the next adjacent radial arm —5—. These ropes tend to brace 25 the entire structure and may, if desired, be 30

used for hanging clothes, although not primarily designed for that purpose.

What I claim is:

A clothes drier comprising an upper and a lower collar, a series of radially extending spaced arms positioned between respective flanges, pins passed through said arms and said flanges for pivotally connecting the same, said pins having heads provided with openings, a series of brace bars carried by the lower collar and pivotally connected to the radially extending arms respectively, a cross bar secured upon the end of each radial arm, said cross bar having a pair of openings upon each side of said arm, a clothes rope strung through the openings in said pins and successively through the outer openings in a cross bar and through the opening in the next succeeding pin, and a brace rope having its intermediate portion passed through the inner openings in said cross bar and its opposite ends provided with means for engagement with the ends of adjacent cross bars.

In witness whereof I have hereunto set my hand this 24th day of January, 1916.

AUGUST TUTAY.
